DESIGN FOR A PLATE.

Design No. 12,728, dated January 31, 1882.

UNITED STATES PATENT OFFICE.

OSCAR S. STRAUS, OF NEW YORK, N. Y.

DESIGN FOR A PLATE.

SPECIFICATION forming part of Design No. 12,728, dated January 31, 1882.

Application filed December 27, 1881. Term of patent 7 years.

To all whom it may concern:

Be it known that I, OSCAR S. STRAUS, a citizen of the United States, residing at New York, county and State of New York, have invented and produced a new and original Design for Plates, of which the following is a specification, reference being had to the accompanying drawing, forming part thereof.

This design is intended to be applied by any suitable means to children's food-plates as an ornament thereto, and also as an instructive device.

It consists in the arrangement on the upper surface of plates of the alphabet in capital letters, also in small or lower-case letters, numeral figures, an imitation of the face and hands of a clock, and plain and ornamental lines and other configurations separating the various parts of the design.

The drawing, which represents a plan view of a plate, *a*, shows the alphabet of capital letters *b b* placed around the rim. The alphabet of small or lower-case letters *c c* is placed inside the alphabet *b b*, with the corresponding letters adjacent. A plain dividing-line, *d*, separates the two alphabets. Inside the lower-case alphabet *c c* is the ornamental line *e*, and within this are arranged the numeral figures *f f*. The numbers are shown ranging up to 20; but if desired they may be arranged in consecutive order up to 26, adjacent to each of the letters of the alphabet. Occupying the center of the plate is a representation of the face of a clock, *g g*, with one of the hands, *h*, pointing to twelve and the other one, *i*, to six, and

against these hours respectively are placed the words "Dinner" and "To bed." The interior of the clock-face is further ornamented by the scroll-work *j*.

The design may be in any color or combination of colors, and be impressed, marked, or printed on the plates by any of the ordinary suitable means.

To change the relative positions of the two alphabets and numeral figures would be an immaterial change as regards the general designs, and it is evident they may be impressed, marked, or printed with the other parts of the design on other than circular plates. The words "Dinner" and "To bed" may also be left off the face of the clock.

I am aware that the alphabet and numerical figures have before been applied to goods of this description as an instructive design thereon.

I claim—

The new and original design for plates herein shown and described, consisting of the representation of the face of a clock located in the center thereof and numeral figures and the capital and lower-case alphabets arranged around the same.

In witness whereof I have hereunto set my hand, at New York, county and State of New York, this 23d day of December, A. D. 1881.

OSCAR S. STRAUS.

In presence of—

JAMES A. HUDSON,
WALTER LARGE.
